UNITED STATES PATENT OFFICE.

SHURE LARSON, OF NORWAY, IOWA.

LOCK.

Application filed April 5, 1924. Serial No. 704,405.

This invention relates to permutation locks used mainly for doors, and the object of the invention is to produce a lock of this type which is very simple in construction and operation; capable of almost infinite variation; not easily pickable, and being constructed without springs; is very durable.

The invention is fully disclosed in the description and claims following, reference being had to the accompanying drawing, in which:

Fig. 1 is a side elevation of a lock embodying the invention as applied to a gravity door-latch hereafter referred to. Fig. 2 is a cross-section of the same, in the line 2—2 of Fig. 1, looking toward the left. Fig. 3 is a sectional view, longitudinal to the lock casing, showing the operating parts of the lock in full. Fig. 4 is a cross-section of the same in the line 4—4 of Fig. 3. Fig. 5 is a cross section in the line 5—5. Fig. 6 is a side view of a blank or "dummy" lock-bar.

In Fig. 1 the lock is shown as a locking member for a swinging, gravity latch 5 shown in Letters Patent No. 1,485,620 issued to this inventor March 4, 1924. In this case the lock is set in a mortise 6 of the door 7, suitably secured therein, as by screws 8, and locks the door by the abutment of the lock-bolt against the latch-bar, as shown. For general use the lock casing 9 is provided with flanges 10, and is set in a mortise and fastened to the edge of the door in the usual way. The bolt 11 in this case enters a socket in the door-jamb (not shown) in a manner so familiar as to need no description or illustration.

The lock is composed of but few, and these very simple parts. In a rectangular casing 40 is assembled slidably a gang of lock-bars or plates 12, all engaging rockably, as by notch 13 and tongue 14, with the bolt 11. One or more of the plates, preferably all of them, for the sake of better security, are provided 45 with a depending lug 15, which drops into a slot 16 in the bottom of the casing when in the unlocked position, and in a similar slot 17 when in the locking position. The under sides of the plates are notched at 18 (and at 19 for a double-key lock), the notches coinciding operably with key-holes 20 and 21 in the sides of the casing. In width the notches may be all alike, but vary in depth to coincide with varying steps in 50 the wing of the key, as shown in Figs. 4 and 5. In these figures the variations are shown

as symmetrical, so that the key may operate from either side, but in many locks this would not be necessary, and the variations might extend to the whole gang. In a gang 60 of ten members, as herein indicated, the possible changes would be almost innumerable.

It will be evident that the turning of a key corresponding to the stepping of the lock-plates will first lift the whole gang of plates out of their locked position, and then shift them endwise, with a reverse movement as the key is turned in the opposite direction. In the endwise movement the bolt is carried by the plates, and shot in and out of locking 70 position. At each terminus of movement the plates drop by gravity, and are themselves locked by their lugs in the slots of the casing.

The double-key construction is not essential in all locks, but is desirable for locks in office buildings, and the like, since the notching for one key may be all alike, and a single master key serves for all the locks. The notching is preferably, but not necessarily, simpler than that employed for the other key, as will be seen by a comparison of Figs. 4 and 5.

Not all of the plates need to be notched as shown in Fig. 3. One or more would be sufficient to carry the bolt endwise as the key is turned. Accordingly the construction may be simplified by making some of the plates as shown in Fig. 6, to serve as lifting and locking plates, but not as thrust-plates.

A keyless inside locking device is shown in Figs. 1, 2 and 3. To the case is pivoted a trip-lever 22 provided with lateral fingers 23 registering with the slots in the casing. The longer arm of the lever engages the bolt by a stud 24. To the body of the lever is attached a turn-button 25 operable from the inner side of the door. This is necessarily attached after the lock is in place in its mortise, and is most conveniently attached by 100 screwing together, as shown in Fig. 2. Turning the button serves to both disengage the lock-plates from the casing and slide the bolt. In order to do so, however, the release of the lock-plates must precede their sliding. Accordingly the lever is slotted at 26 to provide the necessary lost motion for the double operation. An offset in the casing at 27 admits of the mounting of the lever without projecting laterally beyond the general face 105 of the casing. This is duplicated on each side of the casing, and the lever being sym-

metrical, may be attached at either side when the position of the lock needs to be reversed. The lever, as will be evident, serves as a support for one end of the bolt, and 5 prevents its withdrawal from the casing. But in changing the lock, as is necessary from time to time in club-rooms and the like, it is the work of but a moment to detach the lever, when the bolt and connected 10 plates slide out of the open end of the casing, and the plates may then be shifted at will. A slot 28 is provided for the bolt-stud to play in.

In Figs. 2 and 3 the inner walls of the 15 casing are shown ribbed endwise. This is to prevent any possible releasing of the lock-plates by the use of a sharp instrument applied to an outer plate through the key-hole or other opening, and simultaneously pressing 20 the plates together and lifting them. Even if this were possible in a smooth-walled casing, it would not be so with the side-walls roughened, since the rough surface would hold the adjacent plate from rising with the 25 rest of the gang, and the lock could not thus be released.

Having thus described my invention, I 30 claim;

1. In a lock, a casing, a plate slidably 35 mounted in said casing and having its end edges perpendicularly disposed to its bottom edge and its top edge obliquely disposed in relation to the other edges so as to slant downwardly and rearwardly, said upper 40 edge of the plate being provided with a notch, a bolt in the casing having a detent engageable in the notch, the bottom of said casing being provided with a pair of spaced openings, a detent on the rear end of the 45 plate engageable in said openings, said plate provided with a notch for the reception of a key in order that the rear end thereof may be lifted to release the detent on the

plate from the opening and to slide the plate for moving the bolt. 45

2. In a lock, a casing, a plate slidable in the casing, a bolt in the upper portion of the casing, said plate being disposed below the bolt and having the edge adjacent thereto slanted rearwardly, the forward end of said edge being provided with a notch, a detent depending from the bolt extending into said notch, the lower edge of said plate at the rear end being provided with a detent, the bottom of said casing being provided with 50 spaced openings for receiving the last mentioned detent, and said plate being provided with a slot for the reception of a key in order that it may be rocked to lift the rear end of the plate so as to release the detent on 55 the plate from one of the openings in the casing and so as to slide the plate in the casing for actuation of the bolt.

3. In a lock, a casing, a plate slidably mounted in said casing and having its end 60 edges perpendicularly disposed to its bottom edge and its top edge obliquely disposed in relation to the other edges so as to slant downwardly and rearwardly, said upper 65 edge of the plate being provided with a notch, a bolt in the casing having a detent engageable in the notch, the bottom of said casing being provided with a pair of spaced 70 openings, a rockable member mounted on the bottom of the casing exteriorly thereof and 75 having lateral projecting ends alternately projectable through the openings in the bottom of the casing, a detent on the rear end of the plate engageable in said openings, said plate being provided with a notch for 80 the reception of a key in order that the rear end thereof may be lifted to release the detent on the plate from the openings and to slide the plate for moving the bolt.

In testimony whereof I affix my signature.
SHURE LARSON.
